UNITED STATES PATENT OFFICE

EDSON R. WOLCOTT, OF PORT ARTHUR, TEXAS, ASSIGNOR, BY MESNE ASSIGNMENTS, TO THE TEXAS COMPANY, OF NEW YORK, N. Y., A CORPORATION OF DELAWARE

TREATING HYDROCARBONS

Application filed June 14, 1924. Serial No. 719,958.

This invention relates to the treatment of hydrocarbons with certain materials to effect a conversion of higher boiling hydrocarbons into lower boiling hydrocarbons, and relates particularly to improvements in methods of treatment in which metallic halids, such as aluminum chlorid, are employed.

I have found that if the hydrocarbons be heated or distilled in the presence of a metallic halid, such as aluminum chlorid, and if the heating or distillation be carried on in the presence of hydrogen chlorid, or while introducing the hydrogen chlorid into the still, that an effectual conversion of higher boiling point products into lower boiling products may be obtained. The addition of the hydrogen chlorid insures an even and smooth operation of the still and materially increases the yield of lower boiling products.

The invention is such that it can be most conveniently described by reference to certain apparatus adapted for carrying out the process. The accompanying drawing is a dia-

grammatic elevation of an apparatus suitable for this purpose.

In the apparatus thus illustrated a still 10 is arranged to be heated by any suitable heating means (not shown) and provided with a charging line 11 for introducing the hydrocarbon material to be treated, a charging conduit 12 for admitting the treating material, and a draw-off pipe 13 for drawing off residue. The still is equipped with a vapor line 14 which may extend to one or more air condensers 15, or other suitable refluxing or fractionating means, from which a vapor line 16 extends to a condenser 17 provided with an outlet 18.

For introducing the hydrogen chlorid a pipe 19 is provided which preferably depends into the still to a point near the bottom thereof. The pipe 19 may terminate in one or more spray pipes, as the perforated pipe 20, in order to thoroughly diffuse the hydrogen chlorid through the mass in the still. If desired, a layer of porous or permeable material may be placed in the still and the hydrogen chlorid caused to be introduced by diffusion through the porous substance thereby admitting the gas in a finely divided state and

thoroughly commingling it with the materials in the still.

In the operation of the process the hydrocarbon material to be treated, which may be a petroleum product such as gas oil, or kerosene, or other hydrocarbon oil which it is desired to convert into a lower boiling oil, is introduced through the pipe 11. A suitable metallic halid, preferably anhydrous aluminum chlorid, is charged through the pipe 12, either in the form of the lump or pulverulent chlorid or in the form of a liquid obtained by mixing the chlorid with a suitable solvent or carrier, such as hydrocarbon oil or other suitable protective medium in which the chlorid is dissolved or contained. The hydrochloric acid gas is introduced through the pipe 19 and thence through the spray pipe 20, or through porous material or other suitable diffusing means, into the mass in the still. The lower boiling point product obtained may be removed as a condensate through the condensate outlet 18.

The use of mixing, stirring, or scraping apparatus which has hitherto been considered necessary in carrying on the treatment of oils with aluminum chlorid is practically dispensed with in the practice of my invention, since the passage of the hydrogen chlorid gas through the mass in the still produces an effective agitation tending to prevent the sludge and tarry matters from collecting and coking in the bottom of the still and bringing about good contact between the catalyst and the hydrocarbon material. Stirring, agitating or scraping mechanism may, however, be employed, if desired.

An idea which induced the present invention was that by passing the hydrogen chlorid through the hydrocarbon material in the presence of aluminum chlorid (Al_2Cl_6) it might be possible to cause a hydrogenating effect by combining the hydrogen with the heavier hydrocarbons to increase the yield of lighter and more saturated hydrocarbons, while at the same time the chlorin would operate to regenerate the aluminum chlorid. It may be, however, that the reaction is not a hydrogenating one; in fact, I do not undertake to explain the chemical reactions which

occur in the practice of my invention. It is sufficient to state that in conducting the treatment of hydrocarbons with a treating material, such as aluminum chlorid, the effectiveness of the operation is increased by the addition of extraneous hydrogen chlorid.

In one method of conducting my process the hydrocarbon material is first saturated with hydrogen chlorid, after which the aluminum chlorid is added and the distillation carried on. In the preferred method of operation, however, the hydrogen chlorid gas is introduced into the still during the distillation.

The hydrogen chlorid employed in the practice of the invention may be in the form of dry gas or moist hydrogen chlorid or hydrochloric acid may be employed, since the presence of moisture or the aqueous solution causes the production of hydrogen chlorid due to the decomposition of the aluminum chlorid by water. If desired, water itself may be added to the treating vessel or moist oil may be admitted thereto, the presence of the moisture insuring the production of the necessary hydrogen chlorid.

Obviously, various modifications of the invention may be effected without departing from the spirit and scope of the invention. The true scope of the invention is defined in the appended claims.

What I claim is:

1. The process of treating hydrocarbon oils to effect conversion of higher boiling hydrocarbons into lower boiling hydrocarbons which comprises charging a high boiling petroleum oil and a catalyst consisting solely of anhydrous aluminum chloride to a still, maintaining said still at a temperature sufficient to effect material conversion of the oil therein, introducing hydrogen chloride into said still to thoroughly commingle with the oil and aluminum chloride, whereby a smooth evolution of vapors is obtained and the aluminum chloride is maintained in an active condition, condensing the evolved vapors to form a distillate of low boiling hydrocarbons, and withdrawing, before substantial accumulation of coke occurs, the residual liquid from the still for disposal without further treatment.
2. The process of treating hydrocarbon oils to effect conversion of higher boiling hydrocarbons into lower boiling hydrocarbons which comprises subjecting a higher boiling petroleum oil to distillation temperatures in the presence of a catalyst consisting solely of anhydrous aluminum chloride, intimately commingling hydrogen chloride with the hot mixture of oil and aluminum chloride to produce an even evolution of vapors of low boiling hydrocarbons and to prevent the oil and aluminum chloride from coking, subjecting the evolved vapors to dephlegmation to produce a vapor fraction of the desired quality and withdrawing the unvaporized residue, which is not returned to the still,

when the reaction has proceeded to the desired extent.

In witness whereof I have hereunto set my hand this 22nd day of May, 1924.
